ELECTRICAL FUSED CUTOUT

Leonard J. Linde and David C. Hubbard, Centralia, Mo., assignors to A. B. Chance Company, Centralia, Mo., a corporation of Missouri

Application October 23, 1946, Serial No. 705,010

15 Claims. (Cl. 200—117)

1

The present invention relates to electrical fused cut-outs, and is particularly concerned with fused cut-outs of the simpler type, commonly called open type, which are adapted to be used upon high tension lines for providing a fused connection between the line and an electrical apparatus, or between the line and ground.

One of the objects of the present invention is the provision of an improved fused cut-out of the open type, which is simple, which has a minimum number of parts, which is efficient, which may carry a plurality of fuses, which is positive in its action, and which is easy to re-fuse.

Another object of the invention is the provision of an improved fused cut-out of the class described, which is adapted to effect a good contact with the fuse and with the connecting lines, and which is adapted to break the circuit at the fuse with a minimum amount of arcing in a minimum amount of time, and the parts of which are adequately insulated and so constructed that there is practically no danger of arcing over after the fuse has cut out the circuit.

Another object of the invention is the provision of an improved fused cut-out of the open type, in which the moving parts are adequately protected from the weather and from moisture, and in which the resiliently actuated arm for separating the fuse terminals is so constructed that its movement to open position is cushioned, thus relieving the castings, cemented joints, and porcelain insulator from shocks incident to the opening of the cut-out.

A further object of the invention is the provision of an improved cut-out of the class described, in which the operating spring for moving the movable arm into the open position acts in a dual capacity for resiliently urging the arm into open position, and also absorbs the shock or jar which is occasioned by the arm when it reaches the end of its travel.

Other objects and advantages will be apparent from the following description and the accompanying drawings, in which similar characters of reference indicate similar parts throughout the several views.

Referring to the drawings, of which there are two sheets,

Fig. 1 is a side elevational view of a fused cut-out embodying our invention, the dotted lines showing the movable arm in the open position, after the fuse has been blown and the circuit opened;

Fig. 2 is a front elevational view of the fused cut-out;

2

Fig. 3 is a fragmentary top plan view of the end of one of the arms, showing the contact arrangements for engaging a plurality of fuse units;

Fig. 4 is a fragmentary sectional view of the mounting for the lower movable contact arm, showing the position which the parts assume when the arm is in its open position and the spring is absorbing the shock;

Fig. 5 is a fragmentary sectional view, taken on the plane of the line 5—5 of Fig. 4;

Fig. 6 is a fragmentary sectional view, taken on the plane of the line 6—6 of Fig. 1, looking in the direction of the arrows, showing the terminal connector by means of which the leads are connected to the fused cut-out.

The fused cut-outs 10 constructed according to our invention preferably include a cross arm bracket 11, an insulator mounting bracket 12, a porcelain insulator 13, an upper arm assembly 14, and a lower arm assembly 15.

The device preferably supports one or more fuse units 16, which are readily removable by means of the usual operating poles, having hooks or headed operating pins at their operating ends.

The cross arm bracket may consist of a pair of channelled metal members 17, 18, each of which has its web provided with a pair of through bores 19, 20 for passing the clamping screw bolts 21, 22, having nuts 23, 24, and spring washers 25.

The heads of the bolts 21, 22 are disposed between the side flanges of one of the channelled members 18, thus holding them from rotation while the nuts are being secured.

One of the channelled members 18 may be longer than the other to provide space for the securing of an additional screw bolt 26, which passes through an aperture in the yoke of channel 18 and through an aperture in the supporting flange and an aperture in the supporting flange 27 of the insulator mounting bracket, thus securing the end of the insulator mounting bracket to the cross arm bracket.

The screw bolt 26 is likewise provided with a nut and spring washer.

The insulator mounting bracket 12 comprises a strip of sheet metal, such as steel, having the attaching flange 27 extending at substantially right angles, and an aperture to receive the bolt 26, and having its other end formed into a cylindrical clamping member, which passes around a cylindrical portion 29 of the insulator 13, to which it is clamped by means of a screw bolt and nut 30, which passes through the body of the bracket 12 and through the end of the strip which projects radially from the cylindrical formation 28.

The insulator 13 may comprise any suitable form of porcelain insulator, but it is preferably provided with the centrally located cylindrical portion 29 and a multiplicity of downwardly sloping skirts 31 above and below the bracket 12.

At its upper and lower ends the insulator 13 is preferably formed with a cylindrical socket 32, and the insulator is preferably glazed overall to shed water and improve its insulating characteristics.

The upper arm 14 may consist of a cast metal member having a circular body flange 33 adapted to engage and overlap the end of the insulator and to overlap the walls of the socket 32; and the body flange 33 supports a depending anchoring formation 34, which may consist of a cylindrical body having a pair of side ribs 35 for preventing rotation and having an annular end rib 36 for anchoring the body axially in a packing of cement 37, which fills the socket 32 and anchors the casting 14 to the insulator 13.

The body flange 33 supports an upwardly extending partially circular enlargement 38, which has sufficient body to be provided with an aperture 39 for receiving a connector bolt 40. The side of the enlargement 38 is preferably formed with a V-shaped groove 41 extending diametrically across the bolt aperture 39 and adapted to receive wires of different sizes.

The screw bolt 40 has a threaded shank and a partially circular head 43 provided with a through bore 44 for receiving a terminal wire.

The head 43 preferably has a pair of lateral extensions 45, which extend axially with respect to the hole 44, and are partially cylindrical for engaging the wire that passes through the bore 44. The extensions 45 may be reinforced by a rib 46 extending the full length of the head 43, with its extensions 45.

The enlargement 38 may have plane sides, but is preferably formed with a partially spherical socket 48 surrounding the bore 39 for receiving the shank of the screw bolt 42 and part of the head 43.

The socket 48 has suitable depth, proportioned with respect to the elevation of the V-shaped groove 41, so that a wire passing through the bore 44 and clamped against the cylindrical extensions 45 of the screw bolt is engaged on the opposite side by the V-shaped groove 41.

A nut 49 on shank 42 serves to clamp the nozzle wire in the terminal connector.

The arm 14 extends outwardly from the enlargement 38, and may consist of a bottom flange 50 and a reinforcing rib 51. Both the bottom flange 50 and the reinforcing rib 51 may taper toward a neck 52 at the outer end of the arm 14, which is provided with a flat head 53 of substantially rectangular shape.

The head 53 may support a resilient fuse-engaging clip 54, which may consist of a strip of resilient steel that is of substantially U-shape and adapted to fit on the end of the head 53.

Each of the legs of this U-shaped clip 54 extend beyond the head 53 and in spaced relation to the neck 52, where the clip has a diagonally outwardly curved portion 55, terminating in a cylindrical bead 56.

The reinforcing rib 51 terminates short of the head 53 so as to prevent it from interfering with the buttons of the fuse unit. The arm 14 curves outwardly at its juncture with the head 53, forming a diagonal wall 57 opposite the diagonal portion 55 of the clip 54, which provides a V-shaped

opening, into which the cable of a fuse unit may be wedged.

Two such openings are provided by the clip, one on each side of the arm 14, so that two fuse units may be simultaneously mounted, or one may be used to support a new fuse before the old fuse is taken out, when a change in fuse capacity is made, without breaking the circuit.

The clip 54 may be supported on the head 53 by means of a metal band 58, which extends completely around the clip, and around the head, to both of which it is secured by dipping the assembly in solder. The band 58 is of sufficient strength to exert a wedging and clamping action on the clip to hold it on the head 53; and it may be secured by driving it on endwise over the U-shaped yoke of the clip 55 and over the head, the solder being employed merely to hold it in place.

Thus the upper arm is rigidly secured to the top of the insulator 13, from which it projects at substantially right angles to hold the upper end of the fuse unit 16, further to be described.

The lower movable arm 15 is preferably pivotally supported by means of screw bolt 59 upon a casting 60. This casting may have a substantially cylindrical anchoring body 61, which preferably has a cylindrical bore 62 for housing a helical spring 63. The end of the cylindrical body 61 preferably has a radially extending flange 64 for covering the cement 65, which secures the body in the socket 32 and overlaps the end of the insulator 13.

The exterior of the cylindrical body 61 may be provided with corrugations 66 or any other suitable anchoring formation. The casting 60 also supports a pair of depending housing flanges 67, 68, which extend downwardly far enough to enclose the lever 15 and spring 63 in both of its positions.

At the rear side of the casting 60 the housing flanges may be thickened at 69 and spaced from each other by a slot 70 of sufficient thickness to receive the pivotally mounted end 71 of the lever 15. The slot 70 is enclosed by a rear curved wall 72 extending above, behind, and below the end 71 of the lever 15.

The flanges at the slot 70 are provided with aligned bores for receiving the screw bolt 59, upon which the lever is pivoted. The casting 60 also has a downwardly and rearwardly extending circular enlargement 73, which has a downwardly and rearwardly extending V-shaped groove like the groove 41, previously described, for providing a clamping surface opposed to a connector bolt 14, like the connector bolt 40, previously described.

This terminal connector may in all ways be similar in construction to the one described at the top of the device on the arm 14, and it is provided with a similar nut and spring washer. The hole in the bolt in this case preferably extends downwardly, and rearwardly in the direction in which the terminal wire is most likely to extend.

The movable lever or arm 15 may consist of a cylindrical rod, which is provided at its rear end 71 with a flattened portion having an aperture serving as a bearing for the screw bolt 59, on which it is pivotally mounted.

At its opposite end the rod may be flattened in a plane transverse to the end 41, having a flat portion 75, which may be formed into a head, like the head 53 previously described, so that it may be provided with a spring clip 54 and a metal band 58 substantially as described with respect to the upper arm 14.

In order to make the fuse units 16 of shorter

length and to conserve material the arm 15 has an obtuse bend at the point 76 so that the arm has a horizontally extending portion 77 and a diagonally and upwardly extending portion 78. This brings the head 75 and clip 74 into a position below the head on the upper arm 15, but extending forwardly of the head on the upper arm 14.

The tapered slots 79, 80 into which the cables of the fuse unit 16 are drawn both extend in such a direction that the pull exerted on the cable tends to pull the cable into the tapered slots 79, 80. The arm 15 is preferably spring pressed downwardly by means of a helical spring 63, the structure of which is best shown in Figs. 4 and 5.

This spring has a helical portion 81, which may extend when expanded a full length of the bore 62, and may also project downwardly between the housing flanges 67, as shown in Fig. 4. The upper end of this spring is bent laterally, and the laterally bent portion 82 extends over to the inner wall of the spring, where it has a downwardly extending leg 83.

This leg extends downwardly the full length of the helical spring 81 and projects beyond it, having a U-shaped formation 84 of sufficient length to receive the end portion 71 of lever 15, which is located in the U-shaped bight 84 below the helical portion 81.

The bight 84 has an upwardly extending leg 85, which preferably is located diametrically opposite to the leg 83 in position to engage the opposite inner wall of the helical coil. The length of the leg 85 is such that it guides the lever portion 71 throughout its full range of movement.

In order that the U-shaped end 84 may advantageously engage the lever 15 it is bent rearwardly at 86 with an obtuse angle. The lever portion 71 is also preferably provided with an upwardly extending lug 87, having an abrupt shoulder 88 on the rear side and a sloping shoulder 89 on the front side. The lug 87, by means of its abrupt shoulder 88, prevents the coils of spring 63 from sliding downwardly on the lever 15 when it is in the position of Fig. 4; that is, the dotted line position of Fig. 1.

The housing flanges 67 are also preferably provided with a pair of inwardly extending stop flanges 90, 91, these being preferably staggered and located to engage underneath the lowermost helical coils of the springs 63 on each side, when the spring is expanded to its maximum position.

The helical spring 63 is placed under a predetermined initial compression so that it is confined between the end wall 92 of the cylindrical bore 62 and the stop lugs 90, 91. The spring may be inserted in the bore 62 by threading it on the lugs 90, 91 while grasping the bight 84 with a suitable tool.

The fuse unit 16 may consist of a tube of insulating material, such as fiber board, which is provided at each end with an insulating plug 93 of suitable insulating material, such as rubber, having an aperture for passing the cables 94, 95.

The plugs 93, when forced into the tube 96, grip the cables 94 and hold the tube in predetermined position on the cable assembly. The two inner ends of the cables 94, 95 are joined to a fusible metal link, preferably by fusing the link to the cable in each case; and the link is the element which melts upon passage of a current of predetermined amperage.

Each cable 94, 95 is formed at its end with a closed loop 97, 98, which may be slightly oval and longer in its axial dimension, due to the mode of

its formation. The loop may be the point at which two strands of the cable are folded back upon each other, the strands being twisted together to form the main cable bodies 94, 95, and each cable being provided with a button 99, 100 adjacent each loop.

The buttons 99, 100 may consist of metal discs or insulating fiber board, each being provided with an aperture large enough to pass the cable, but not large enough to pass the loops 97, 98. Thus the buttons 99, 100 serve as thrust members for engaging the upper side of the upper arm 14 and the lower side of the lower lever 15.

The loops serve to be engaged by a headed pin on a switch actuating pole or other operating tool.

The fuse may be removed by engaging the pin and operating pole in the upper loop 97 and pushing upwardly and backwardly on the pole to draw the cable 94 out of the groove 79 or 80 in which it is wedged on the upper arm. Once the button and cable have cleared the clip 54 on the upper arm, the spring 63, which actuates the lower arm 15, may be permitted to pull the lower arm 15 downwardly, the fuse unit 16 following it until the arm 15 reaches the point of engagement with the inner surface of the bight 84 of the spring 63, which serves as a stop surface.

The lugs 90, 91 on the tubular part of the casting 66 serve to prevent the spring from coming out of its socket 62, and hold the lever 15 in the lower dotted line position. When a fuse is to be inserted, it hangs from an operating pole by means of the pin on the pole engaging in the upper loop 97; and with the fuse hanging, the pole is so manipulated that the lower cable 95 is inserted in one of the slots 79 or 80 of the lower arm 15.

This can be done without interference on the part of the upper arm 14 because of its shortness. Once the cable 95 has its button 100 engaged with the lower surface of the arm 15, the operator may pull upwardly on the cable by means of the upper loop until the arm 15 reaches its uppermost position slightly beyond that shown in Fig. 1 in full lines. Then the loop 97 may be so manipulated that the cable 94 passes into a groove 79 or 80 on the upper arm 14; and thereafter the arms may be permitted to support and exert a pull on the fuse unit 16.

The spring pressure on the lower arm tends to pull the fuse unit downwardly and forwardly in such manner as to pull it further into the grooves on both arms, and to maintain a constantly good electrical contact.

The operation of the fused cut-out is as follows: When the current passing through the fuse exceeds a predetermined amount, the fuse link is melted, separating the cable portions 94, 95, which are under tension. The pull between the arms 14, 15 draws the cable portions 94, 95, with their plugs, out of the tube 96, further separating the ends of the cable and aiding in the extinguishment of the arc, which occurs inside the tube 96, where it further tends to be smoothed and extinguished by the confined combustion gases and by the gases driving the cable ends out of both ends of the tube.

The cables then hang loosely from the two arms, but the lower cable may conceivably drop out of the lower arm on some occasions. They are removed by means of the usual switch operating stick, and a new fuse may be inserted as stated above.

During the operation of the cut-out fuse it should be noted that the spring 63 places a down-

ward pressure on the arm 15, urging it apart from the arm 14 at all times. When the arm 15 is released by the fuse unit 16, it moves downward with considerable force and is stopped by the yoke or bight 84 of the spring 63, which in turn pulls downward on the upper end of the spring, compressing the spring against the lugs 90 and 91 to absorb the shock and stop the movement of the arm 15.

Thus the spring 63 is used not only to urge the arm 15 into position to place a tension on the fuse unit, but also to absorb the shock of the movement of the arm 15 when a fuse is blown. This reduces the shocks and breakage of insulators and tends to prevent damage to the cement, by means of which the lower casting is secured to the insulator.

Another feature of the fused cut-out is that the two grooves 79, 80 provided in each arm permit an operator to place a fuse of different capacity in circuit before taking the other fuse out, thus changing the fuse capacity without breaking the circuit.

It will thus be observed that we have invented an improved fused cut-out which is simple in structure, but which provides a safe and certain connection between the fuse unit and the cut-out device, which is easy to re-fuse and easily permits changing of a fuse capacity without breaking the circuit.

The structure of our fused cut-out is simple and economical to manufacture, and it is capable of being used for a long period of time without breakage or necessity for repair. The spring, which urges the arms apart, also absorbs the shock incident to the moving of the movable arm when the fuse is blown, thus taking much strain off the castings, cemented joints, and porcelain insulator, and contributing to the effective life of the fuse.

While we have illustrated a preferred embodiment of our invention, many modifications may be made without departing from the spirit of the invention, and we do not wish to be limited to the precise details of construction set forth, but desire to avail ourselves of all changes within the scope of the appended claims.

Having thus described our invention, what we claim as new and desire to secure by Letters Patent of the United States, is:

1. In a fused cut-out, the combination of a supporting insulator with a pair of fuse supporting arms, one of said arms being rigidly mounted on said insulator, and the other of said arms being pivotally mounted, said arms being provided with means at their ends for removable attachment of a fuse unit under tension, and resilient means for urging the pivotally mounted arm away from the rigidly mounted arm, said resilient means also having an element engaging the outer side of the pivotally mounted arm to absorb the shock of movement of said arm upon blowing of the fuse, said resilient means being housed in the lower end of said insulator, and comprising a helical spring reacting against the insulator and said pivotally mounted lever, and having an extension from its end opposite to the lever carrying said element engaging the opposite side of the arm.

2. In a fused cut-out, the combination of an insulator with a spring pressed lever assembly, comprising a metal housing carried by the insulator, a fuse supporting arm pivotally mounted on said housing, a helical spring located in said housing and placed under a predetermined com-

pression by engagement with shoulders at each end, one end of the spring engaging the lever and the other end of the spring having an axial extension engaging on the opposite side of the lever.

5. 3. In a fused cut-out, the combination of an insulator with a spring pressed lever assembly, comprising a metal housing carried by the insulator, a fuse supporting arm pivotally mounted on said housing, a helical spring located in said housing and placed under a predetermined compression by engagement with shoulders at each end, one end of the spring engaging the lever and the other end of the spring having an axial extension engaging on the opposite side of the lever, said axial extension being of substantially U shape and embracing both sides of the lever and extending into said helical spring, whereby the spring urges the lever in one direction to tension a switch unit, and when moved to the limit of its movement in that direction the lever engages the U shaped portion to absorb shock.
10. 4. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
15. 5. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
20. 6. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
25. 7. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
30. 8. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
35. 9. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
40. 10. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
45. 11. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
50. 12. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
55. 13. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
60. 14. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
65. 15. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
70. 16. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.
75. 17. In a fused cut-out, the combination of an insulator with means for supporting the insulator from a cross arm carried by a medial portion of the insulator, said insulator having a cavity in each of its ends, a rigid arm extending transversely to the insulator for supporting a fuse unit, and having an anchoring formation secured in one of said cavities, and a second arm pivotally mounted upon a fixture, said fixture having an anchoring formation secured in the other cavity, whereby said pivotally mounted arm is located to support the other end of a fuse unit, said fixture comprising a substantially cylindrical housing located in the cavity and having a helical spring located in the housing engaging the end of the housing and acting on said pivotally mounted arm.

mounted arm, and stop means carried by said spring for engaging the opposite side of said pivotally mounted arm to absorb the shock of movement of the arm when a fuse blows, and stop means carried by said housing engaging an outer portion of said helical spring for holding the spring in its housing.

7. In a fused cut-out, the combination of an insulator with a pivoted arm assembly, the said insulator having a substantially cylindrical cavity in its end, a spring housing member of substantially cylindrical shape in said cavity, said spring housing having external anchoring formations thereon, cement engaging the anchoring formations and the walls of the cavity to secure the spring housing in the cavity, a fuse tensioning lever pivotally mounted upon said spring housing member and a helical spring located in said spring housing and reacting against the end thereof, said spring acting at its opposite end on the pivotally mounted arm, said arm being provided at its end with means for engaging a fuse unit.

8. In a fused cut-out, the combination of an insulator with a pivoted arm assembly, the said insulator having a substantially cylindrical cavity in its end, a spring housing member of substantially cylindrical shape in said cavity, said spring housing having external anchoring formations thereon, cement engaging the anchoring formations and the walls of the cavity to secure the spring housing in the cavity, a fuse tensioning lever pivotally mounted upon said spring housing member and a helical spring located in said spring housing and reacting against the end thereof, said spring acting at its opposite end on the pivotally mounted arm, said arm being provided at its end with means for engaging a fuse unit, said spring having an axial extension extending from the end of the spring in said spring housing outwardly in said spring and having a laterally turned portion engaging about said lever.

9. In a fused cut-out, the combination of an insulator with a pivoted arm assembly, the said insulator having a substantially cylindrical cavity in its end, a spring housing member of substantially cylindrical shape in said cavity, said spring housing having external anchoring formations thereon, cement engaging the anchoring formations and the walls of the cavity to secure the spring housing in the cavity, a fuse tensioning lever pivotally mounted upon said spring housing member and a helical spring located in said spring housing and reacting against the end thereof, said spring acting at its opposite end on the pivotally mounted arm, said arm being provided at its end with means for engaging a fuse unit, said spring housing member being provided on its inside with inwardly extending lugs engaging the coils of the spring adjacent said lever to prevent the spring from moving out of said housing.

10. In a fused cut-out, the combination of an insulator with a pivoted arm assembly, the said insulator having a substantially cylindrical cavity in its end, a spring housing member of substantially cylindrical shape in said cavity, said spring housing having external anchoring formations thereon, cement engaging the anchoring formations and the walls of the cavity to secure the spring housing in the cavity, a fuse tensioning lever pivotally mounted upon said spring housing member and a helical spring located in said spring housing and reacting against the end thereof, said spring acting at its opposite end on

the pivotally mounted arm, said arm being provided at its end with means for engaging a fuse unit, said spring housing member being provided on its inside with inwardly extending lugs engaging the coils of the spring adjacent said lever to prevent the spring from moving out of said housing, and an axial extension extending from the inner end of said spring into engagement with the outer end of said lever so that the spring is compressed to absorb shock when the lever moves outwardly a predetermined amount.

11. In a fused cut-out, the combination of an insulator with a pivoted arm assembly, the said insulator having a substantially cylindrical cavity in its end, a spring housing member of substantially cylindrical shape in said cavity, said spring housing having external anchoring formations thereon, cement engaging the anchoring formations and the walls of the cavity to secure the spring housing in the cavity, a fuse tensioning lever pivotally mounted upon said spring housing member and a helical spring located in said spring housing and reacting against the end thereof, said spring acting at its opposite end on the pivotally mounted arm, said arm being provided at its end with means for engaging a fuse unit, the said spring housing member being provided with a radial flange engaging the end of the insulator, and with a pair of outwardly projecting parallel guide flanges for guiding the lever in its pivotal movement.

12. In a fused cut-out, the combination of an insulator with a pivoted arm assembly, the said insulator having a substantially cylindrical cavity in its end, a spring housing member of substantially cylindrical shape in said cavity, said spring housing having external anchoring formations thereon, cement engaging the anchoring formations and the walls of the cavity to secure the spring housing in the cavity, a fuse tensioning lever pivotally mounted upon said spring housing member and a helical spring located in said spring housing and reacting against the end thereof, said spring acting at its opposite end on the pivotally mounted arm, said arm being provided at its end with means for engaging a fuse unit, the said spring housing member being provided with a radial flange engaging the end of the insulator, and with a pair of outwardly projecting parallel guide flanges for guiding the lever in its pivotal movement, said guide flanges extending backwardly to support a pivot pin for pivotally mounting said lever, and the said guide flanges being provided with an enclosing wall above, behind and below the pivot of said lever for excluding ice accumulations.

13. In a fused cut-out, the combination of an insulator with a pivoted arm assembly, the said insulator having a substantially cylindrical cavity in its end, a spring housing member of substantially cylindrical shape in said cavity, said spring housing having external anchoring formations thereon, cement engaging the anchoring formations and the walls of the cavity to secure the spring housing in the cavity, a fuse tensioning lever pivotally mounted upon said spring housing member and a helical spring located in said spring housing and reacting against the end thereof, said spring acting at its opposite end on the pivotally mounted arm, said arm being provided at its end with means for engaging a fuse unit, the said lever comprising a metal member formed to extend substantially normal to the insulator and thereafter having an obtuse bend, and a diagonally and upwardly extending

11

elongated end portion for engaging the fuse unit.

14. In a fused cut-out, the combination of an insulator with a pivoted arm assembly, the said insulator having a substantially cylindrical cavity in its end, a spring housing member of substantially cylindrical shape in said cavity, said spring housing having external anchoring formations thereon, cement engaging the anchoring formations and the walls of the cavity to secure the spring housing in the cavity, a fuse tensioning lever pivotally mounted upon said spring housing member and a helical spring located in said spring housing and reacting against the end thereof, said spring acting at its opposite end on the pivotally mounted arm, said arm being provided at its end with means for engaging a fuse unit, the said lever comprising a metal member provided at its free end with a relatively wide integral flat portion, a U-shaped wire fitting about said flat portion and having diverging ends, said wire being soldered to the flat portion and forming V-shaped grooves on both sides of the lever for receiving a fuse unit cable.

15. In a fused cut-out, the combination of an insulator with a pivoted arm assembly, the said insulator having a substantially cylindrical cavity in its end, a spring housing member of substantially cylindrical shape in said cavity, said spring housing having external anchoring formations thereon, cement engaging the anchoring formations and the walls of the cavity to secure the spring housing in the cavity, a fuse tensioning lever pivotally mounted upon said spring housing member and a helical spring located in said spring housing and reacting against the
